(57) **CLAIM**

The ornamental design for a light fixture, as shown and described herein.

DESCRIPTION

FIG. 1 is a top plan view of a light fixture showing our design;

FIG. 2 is a right side elevational view thereof;

FIG. 3 is a left side elevational view thereof;

FIG. 4 is a bottom plan view thereof;

FIG. 5 is a rear elevational view thereof;

FIG. 6 is a front elevational view thereof;

FIG. 7 is a perspective view thereof; and,

FIG. 8 is another perspective view thereof.

The broken line showing of environmental structure in the figures is for illustrative purposes only and forms no part of the claimed design.
